[57] **CLAIM**

The ornamental design for a periodontal brush and
mounting bracket, as shown and described.

DESCRIPTION

FIG. 1 is a front elevational view of a combined electric
periodontal brush and mounting bracket showing our
new design;

FIG. 2 is a side elevational view thereof, the opposite
side being a mirror image;

FIG. 3 is a rear elevational view thereof;

FIG. 4 is a bottom plan view thereof;

FIG. 5 is a top plan view thereof;

FIG. 6 is a front elevational view of the brush, the
mounting bracket being omitted;

FIG. 7 is a side elevational view thereof;

FIG. 8 is a rear elevational view thereof;

FIG. 9 is a bottom plan view thereof;

FIG. 10 is a top plan view thereof.

The mounting bracket is omitted from FIGS. 6 through
10 for purposes of disclosure.
